FIRE EXTINGUISHER

Fred Albert Dodelin, Glen Ridge, N. J., assignor
to Pyrene Manufacturing Company, Newark,
N. J., a corporation of Delaware

Application April 10, 1937, Serial No. 136,047

1 Claim. (Cl. 169—31)

This invention relates to fire extinguishers of the type wherein a cartridge containing highly compressed gas is employed as a source of pressure fluid which, when the cartridge is punctured, is rendered available within the fire extinguisher as a pressure medium for expelling the extinguishing liquid therefrom.

An important object of the invention is to provide a generally improved extinguisher of the type mentioned which is simple in construction, easily assembled, inexpensive to manufacture, reliable in operation, and which may be easily reconditioned for use by replenishing the supply of extinguishing liquid and by substituting a new cartridge for the one previously discharged.

Other objects and advantages of the invention will become apparent from the following description, taken in connection with the accompanying drawings, in which—

20 Fig. 1 is a plan view of a fire extinguisher embodying the invention.

Fig. 2 is a fragmental view showing the fire extinguisher partly in elevation and partly in section.

25 Fig. 3 is an enlarged central, vertical, sectional view of the cartridge-piercing and valve-actuating head, and

Fig. 4 is a horizontal, sectional view taken on line 4—4 of Fig. 3.

30 The extinguisher, herein shown, includes a liquid container 10, the cylindrical side wall and the upper end wall of which are formed integral with each other, and the lower end wall of which comprises a base 11, having an upstanding marginal flange 12, within which the lower end of the cylindrical wall is so secured as to provide an air and liquid-tight joint. To the upper end wall of the container 10, there is connected an annular fitting or head-support 14, having a depending skirt 15, which serves to insure the container against being filled beyond a predetermined level so as to provide an air space above the liquid level which is sufficiently large to accommodate a substantial quantity of pressure fluid when initiating the operation of the extinguisher in the manner hereinafter more particularly described.

35 The head-support 14 is adapted to detachably receive a cartridge-piercing and valve-actuating head 16. This head includes a plug-like fitting 17, the lower end of which is adapted for screw-threaded connection with the annular fitting or head-support 14 and is there provided with a gasket-receiving flange 18, with which is associated a gasket 20, adapted to be forced into im-

pinging engagement with the upper or seating surface of the fitting 14 so as to provide an air and liquid-tight seal between such fitting and head when the extinguisher is conditioned for use. The fitting 17 is provided at its lower end with 5 a depending internally screw-threaded flange 21, adapted to receive the externally screw-threaded neck portion of the sealing head 22 of a cartridge 24, carrying a highly compressed gas, such as carbon dioxide, which is adapted to be employed 10 as a source of pressure fluid to expel the extinguishing liquid from the container 10 when the extinguisher is put into operation, the contents of the cartridge being normally retained therein by a suitable seal 25 which is adapted to 15 be punctured under conditions hereinafter more particularly described.

The fitting 17 is drilled or otherwise formed with a chamber 26 in the upper end of which is disposed a screw-threaded plug-like retaining 20 disc 27. Within the chamber 26, there is arranged a piercer-actuating rod 28, the upper end of which projects through the disc 27 and within the lower end of which is carried a screw-threaded stem 30, which is provided at its lower end with 25 a substantially square guide plate 31 and a suitable punch-like piercer 32 by which the cartridge seal 25 may be ruptured. The disc 27 functions in association with the guide plate 31 (the corners of which engage the wall of the chamber 26) as 30 means for maintaining the piercer-actuating rod 28 in a coaxial relation to the chamber 26 so as to insure proper alignment of the piercer 32 with the puncturable area of the cartridge seal 25. Upon puncturing the cartridge seal 25, the 35 pressure medium is directed from the cartridge 24 into the space or chamber afforded intermediate the sealing head 22 and the guide plate 31 (which chamber communicates with the liquid container 10 by way of a pair of apertures 34 40 formed in the depending flange 21), and in order to insure against escape of the pressure medium from the chamber 26 except by way of the apertures 34 there is provided a sealing bellows 35, the lower end of which is in gas-tight union with 45 the piercer-actuating rod 28 and the guide plate 31 and the upper end of which is held in gas-tight union with the fitting 17 by the retaining disc 27.

45 Adjacent the chamber 26 there is formed a similar chamber 36, the bottom wall of which is 50 formed with a valve seat 37 and a liquid discharge port 38, which is coaxial with respect to the valve seat and within which is secured a depending pick-up tube 40, the inlet end of which is located at the bottom of the liquid container 10 and at 55

a slight distance from the lower end wall thereof. Within the chamber 36, there is arranged a valve stem 41, the lower end of which is equipped with a sealing disc 42 which serves as a valve, adapted 5 to be moved into and out of sealing engagement with the valve seat 37, whereby communication of the pick-up tube 40 with a conventional hose-and-nozzle unit 44 may be either severed or established, it being observed that the hose-and-nozzle unit (which is connected to the fitting 17) 10 is maintained at all times in communication with the chamber 36 and that the lower end of the valve stem is substantially square so as to afford a clearance between itself and the wall of the chamber. It will also be observed that the four corners of the lower end of the valve stem 41 engage the wall of the chamber 36 and that the upper end of the valve stem projects through a screw-threaded plug-like retaining disc 45 which 15 is disposed in the upper end of the chamber 36 and serves in conjunction with the lower end of the valve stem as means for maintaining the valve stem in proper position to insure accurate seating of the sealing disc 42 on the valve seat 20 37. In order to insure against the escape of liquid from the chamber 36, except by way of the hose-and-nozzle unit 44, there is provided a sealing bellows 46, the lower end of which is in liquid-tight union with the valve stem and the upper 25 end of which is held in liquid-tight union with the fitting 17 by the retaining disc 45.

In the type of extinguisher to which the present invention is directed, it is desirable to insure opening of the liquid discharge port immediately 30 prior to puncturing the cartridge and to be able to effect such operations through the medium of a single control means. Taking these factors into account, the piercer-actuating rod 28 and the valve stem 41 are so connected by a rocker arm 47 as the valve stem is moved upwardly to open the liquid discharge port 38 the piercer-actuating rod 28 is moved downwardly to puncture the cartridge. The rocker arm 47 is pivotally connected at one end to the upper end of the piercer-actuating rod 28 and is connected at its other end 35 to the upper end of the valve stem 41 at a point where that stem is connected to a lift rod 48, the rocker arm being pivotally supported on a bearing pin or screw 50 which passes through and is supported by the side walls of a cap-like housing 51 which is held in position on the fitting 17 by a plurality of retaining screws 52. In order that unobstructed operation of the rocker arm 47 may be permitted, the pivotal connections 40 between that arm and the piercer-actuating rod 28 and valve stem 41 may be so made as to afford such lost motion (which at the most is only very slight) as is necessary to allow the pivot axes to shift with relation to the rocker arm lengthwise 45 of the same. Surrounding the lift rod 48, is an externally screw-threaded actuating sleeve 54 which is adapted for rotation with relation to the lift rod and is carried within an internally screw-threaded flange 55 projecting upwardly from and 50 forming a part of the cap-like housing 51. To the upper end of the actuating sleeve 54, there is splined or otherwise suitably connected a hand-wheel 56, which is held against removal by a thrust ring 57 secured to the upper end of the lift rod 48. Inasmuch as the actuating sleeve 54, when 55 rotated in a counterclockwise direction as viewed in Fig. 1, moves upwardly, the thrust ring 57 will serve to insure corresponding upward movement of the valve stem 41, which, because of its rocker-arm connection with the piercer-actuating rod 70

28, will then cause that rod to simultaneously move downwardly. In order to insure downward movement of the valve stem 41 and upward movement of the piercer-actuating rod 28 as the actuating sleeve 54 is moved downwardly in response to rotation of the hand-wheel 56 in a clockwise direction as viewed in Fig. 1, there is provided a thrust washer 58 which surrounds the lift rod 48 and engages the upper end of the valve stem 41 and the lower end of the actuating sleeve 54. 10

It is desirable to guard the hand-wheel 56 against accidental displacement, as when the extinguisher is resting dormant in condition for use, and to that end the flange 55 is provided with an encircling yoke 60, adapted to be held 15 by a set screw 61 in any one of a multiplicity of positions of rotary adjustment. This yoke 60 is provided with a socket-like sleeve 62, which is adapted to assume a position of registration with an aperture 64 formed in the hand-wheel 56 so 20 as to permit a retaining pin 65 to be passed through that aperture and into the socket-like sleeve, the retaining pin being preferably connected by a chain 66 to the encircling yoke 60 at a point adjacent the socket-like sleeve thereof. 25 Proper rotary adjustment of the encircling yoke 60 may be determined, at the time the extinguisher is assembled in the factory, by the position that the hand-wheel aperture 64 occupies when the valve stem 41 is in its lowermost or 30 valve-closing position, it being understood that once such adjustment is determined the encircling yoke 60 may be locked on the flange 55 by the set screw 61. Although the retaining pin 65 is adapted to effectively insure against accidental 35 displacement of the hand-wheel 56, as when the extinguisher is resting dormant and is conditioned for use, it may be readily removed in the case of emergency to permit the extinguisher to be placed in operation by turning the hand-wheel in a 40 counterclockwise direction, as a result of which the valve stem 41 is lifted so as to open the liquid discharge port 38 and the piercer-actuating rod 28 is moved downwardly so as to cause the piercer 45 to puncture the cartridge.

Upon opening the liquid discharge port 38 and upon puncturing the cartridge 24, the extinguisher is automatically set into operation by reason of the fact that the pressure medium, as it is released from the cartridge, builds up a pressure 50 over the extinguishing liquid within the liquid container 10 and forces it upwardly through the pick-up tube 40 and out of the hose-and-nozzle unit 44 by way of the liquid discharge port 38 and the chamber 36 (with the latter of which 55 the hose-and-nozzle unit directly communicates), the pressure derived from the contents of the cartridge being such as to effect complete evacuation of the fire extinguishing liquid and at the same time maintain a substantially uniform rate 60 of flow of such liquid throughout the entire discharge period.

Pursuant to an operation of the extinguisher, it may be readily reconditioned for use by removing the valve-actuating head 16 (removal 65 being facilitated by the pair of handles 67 with which the head is provided), running the hand-wheel 56 down to such position that the liquid discharge port 38 will be closed (in which case the retaining pin 65 may be inserted through the aperture 64 and into the socket-like sleeve 62), substituting a new cartridge for the discharged cartridge 24, filling the liquid container 10 to approximately the horizontal center line of the peep or sight window 68 provided in the wall of 70 75

the liquid chamber and then replacing the valve-actuating head 16.

Preferably, the extinguisher is equipped with suitable means to facilitate its being carried from place to place, such means being herein illustrated as including a container-embracing clamping ring 70, having an opening 71 formed therein to accommodate the peep or sight window 68 and provided with wing-like ears 72 to which are connected, as by snap hooks 74, the opposite ends 10 of a shoulder strap 75.

Although only one form of the invention is herein shown and described, it will be understood that various changes may be made without departing from the spirit of the invention or the 15 scope of the following claim.

What is claimed is:

In a liquid fire extinguisher of the cartridge type, a cartridge puncturing and valve actuating head comprising a fitting having a pair of chambers formed therein, a piercer-actuating rod arranged for longitudinal movement within one of 20 said chambers and projecting upwardly there-

from, a valve stem arranged for longitudinal movement within the other of said chambers and projecting upwardly therefrom, a cap-like housing seated on and detachably connected to the upper end of said fitting, a rocker arm pivotally supported above said fitting and within said cap-like housing and pivotally connected at one end to the upper end of said piercer-actuating rod and at the other end to the upper end of said valve stem, a lift rod connected to said valve stem 5 and projecting upwardly through said cap-like housing, an actuating sleeve rotatable on but longitudinally immovable on said lift rod and having a screw-thread connection with the top of said cap-like housing, and a hand wheel rigidly connected to the upper end of said actuating sleeve above said housing for rotating said actuating sleeve and imparting longitudinal movement to said lift rod with resulting movement of said piercer-actuating rod and valve stem in 10 opposite directions.

FRED ALBERT DODELIN.
